UNITED STATES PATENT OFFICE.

JOHN H. HUNT, OF DAYTON, OHIO, ASSIGNOR, BY MESNE ASSIGNMENTS, TO DELCO-LIGHT COMPANY, OF DAYTON, OHIO, A CORPORATION OF DELAWARE.

IGNITION SYSTEM.

Application filed March 26, 1919. Serial No. 285,270.

To all whom it may concern:

Be it known that I, JOHN H. HUNT, a citizen of the United States of America, residing at Dayton, county of Montgomery, 5 State of Ohio, have invented certain new and useful Improvements in Ignition Systems, of which the following is a full, clear, and exact description.

This invention relates to ignition systems 10 for internal-combustion engines, and the chief object is to provide ignition for an engine by utilizing a source of current supply at relatively high voltage.

In carrying out this object I use an ignition coil and timer which are standard as 15 regards the usual types of ignition systems operating on relatively low voltages, and a supply of primary current of relatively high voltage, and provide means whereby a spark 20 will be obtained only upon the separation of the timer contacts.

Other and further objects and advantages 25 of the present invention will be apparent from the following description, reference being had to the accompanying drawings, wherein preferred embodiments of the present invention are clearly shown.

In the drawings:—

Figs. 1 to 4 are wiring diagrams showing 30 different forms of the invention.

In each figure of the drawings a high-voltage battery 20 or other source of current at a voltage considerably higher than ordinarily employed for ignition circuits is 35 grounded at 21, and is connected with an inductive winding 22 wound about a closed magnetic circuit 23. Inductance 22 is connected with resistance 24 which in turn is connected with ignition coil primary 25. Primary 25 is connected with an engine controlled timer 26 connected by ignition switch 27 with a ground connection 28. A condenser 29 is shunted around the timer 26. Ignition coil secondary winding 30 is connected 45 with a spark gap or spark plug 31.

The ignition coil, being a standard type of coil used for low voltage ignition has a high transformation ratio. For this reason, if the inductance 22 were not placed in circuit with the coil, a high secondary voltage would be produced at the instant of the closing of the timer contacts, and a spark would occur prematurely at the gap or plug 31. The inductive winding 22 is constructed 55 so as to have a high inductance when the

current in the winding is small and a comparatively small value when the current has built up to a large value. With this inductance 22 in circuit, the voltage impressed by the battery is divided between the ignition coil primary 25 and said inductance 22 in direct ratio to their inductance at time of closing of timer contacts. Inductance 22 and core 23 are constructed and arranged so that the magnetic circuit is saturated at very low currents, that is, at a fraction of the maximum current normally flowing through it, so that the total energy stored in it, which would react on the timer contacts when the circuit is opened, can be limited, to a value insufficient to cause arcing at the opening of the timer contacts.

By way of illustration, the dimensions of some of the electrical units are given: The ignition coil primary 25 may have 260 turns 75 of number 20 wire, and the secondary 30 may have 12000 turns of number 36 wire. The induction winding 22 may have an inductance of 148 millihenries and may comprise 348 turns of number 20 wire. The 80 core 23 is laminated and has a cross-section $\frac{3}{4}$ inches square, and an opening $2\frac{1}{16}$ inches by $\frac{1}{16}$ inch.

In Figs. 2 to 4 are shown various devices for obtaining a discharge of energy from 85 the inductance 22 at the time of break in a manner such as to obtain a clean or substantially arcless break of the timer contacts. In Fig. 2, a capacity 34 of 20 microfarads is connected in parallel with winding 22. In 90 Fig. 3, the discharge is across carbon blocks 35 and 36 separated by mica insulation 37 .001-inch thick and provided with a discharge path or hole $38\frac{1}{4}$ -inch in diameter. One or both of said carbon blocks may be 95 vented in a suitable manner to provide for the escape of heat generated by the discharge. In Fig. 4 a secondary inductance 40 comprising 3500 turns of number 36 wire cooperates inductively with winding 22 to 100 effect a discharge at the time of break of the primary circuit across a brass ball gap of .006 inches, the balls 41 and 42 being $\frac{3}{8}$ -inch in diameter.

It is to be understood that the invention 105 is not limited to the dimensions given or to the materials described, but that variations of dimensions and substitutions of materials may be made in order to suit the requirements of a particular system. Systems con- 110

structed in accordance with the foregoing description have been found to operate satisfactorily at 110 volts, but it is to be understood that primary current at voltages which vary somewhat from this value can be employed by making the necessary variations in the dimensions of some of the electrical units.

It has been found expedient to provide a discharge gap for the inductance 22 which will discharge at a value slightly above battery voltage, for example, at 125 volts where the battery voltage is 110 volts.

It is apparent from the foregoing description that the present invention provides for the suppression of ignition at the time of closing of the timer contacts while permitting the contacts to open without undue arcing. These provisions permit the use with high voltage primary circuits of ignition coils which are constructed for use with the ordinary low voltage circuits without change in the construction of the coil.

While the forms of mechanisms herein shown and described constitute preferred forms of embodiments of the invention, it is to be understood that other forms might be adopted, and various changes and alterations made in the shape, size, and proportion of the elements therein without departing from the spirit and scope of the invention.

What I claim is as follows:

1. In an ignition system, the combination with an ignition coil having a relatively high transformation ratio; a timer; a current source of relatively high voltage; and electrical means for suppressing ignition at the closing of the timer contacts.

2. In an ignition system, the combination with an ignition coil having a relatively high transformation ratio; a timer; a current source of relatively high voltage; and an inductance in series with the ignition coil primary winding for suppressing ignition at the closing of the timer contacts.

3. In an ignition system, the combination with an ignition coil having a relatively high transformation ratio; a timer; a current source of relatively high voltage; an inductance in series with the ignition coil primary winding for suppressing ignition at the closing of the timer contacts; and means for effecting a discharge of said inductance at the time of opening of said timer contacts in order to prevent arcing at said contacts.

4. In an ignition system, the combination with an ignition coil having a relatively high transformation ratio; a timer; a cur-

rent source of relatively high voltage; an inductance in series with the ignition coil primary winding for suppressing ignition at the closing of the timer contacts; and a discharge gap connected with said inductance providing for the discharge of said inductance at a voltage slightly above the voltage of said current source.

5. In an ignition system, the combination with an ignition coil having a relatively high transformation ratio; a timer; a current source of relatively high voltage; an inductance in series with the ignition coil primary winding for suppressing ignition at the closing of the timer contacts; and a discharge gap consisting of carbon blocks separated by insulation having a discharge passage in alignment with said blocks.

6. In an ignition system, the combination with an ignition coil having a relatively high transformation ratio; a timer; a current source of relatively high voltage; an inductance in series with the ignition coil primary winding for suppressing ignition at the closing of the timer contacts; a secondary inductance cooperating with said series inductance; and a discharge gap for said secondary inductance.

7. In an ignition system, the combination with an induction coil; a timer; a current source of relatively high voltage; and electrical means for suppressing ignition at the closing of the timer contacts.

8. In an ignition system, the combination with an induction coil; a timer; a current source of relatively high voltage; an electrical means for suppressing ignition at the closing of the timer contacts; and for suppressing arcing at the opening of the timer contacts.

9. In an ignition system, the combination with an induction coil; a timer; a current source of relatively high voltage; and a varying inductance for suppressing ignition at the closing of the timer contacts.

10. In an ignition system, the combination with an induction coil; a timer; a current of relatively high voltage; and an inductance for suppressing ignition at the closing of the timer contacts, said inductance being relatively larger at low current values than at high current values.

In testimony whereof I affix my signature.

JOHN H. HUNT.
